UNITED STATES PATENT OFFICE

CHARLES F. EBERT, OF PITTSBURGH, PENNSYLVANIA

SAFETY APPLIANCE FOR SUBMARINES

Application filed May 1, 1929. Serial No. 359,519.

This invention relates to safety appliances for submarines and more in particular to methods and means for providing the crew of a sunken submarine with an ample supply of air during the period of forced submergence.

One of the primary objects of this invention is to provide in a submarine positive means whereby the crew of a sunken submarine may establish communication with the atmosphere to supply their craft with proper air circulation. Another object of this invention relates to a safety appliance which is devoid of floats and which is composed principally of any suitable number of rigid air tubes connected end to end. A further object resides in the construction of a special type of outlet devices whereby the rigid air tubes may be forced out of the submarine without allowing the entrance of sea water therein. Still another object is to provide means for ascertaining whether or not the air tubes have reached a sufficient height above the surface of the sea. Yet another object is to provide outlets which enable the vertical projection of air-tubes above the surface of the sea level, when the sunken submarine assumes a tilted position on the bottom of the sea.

Additional features and advantages of this invention will appear from the following description considered in connection with the accompanying drawings forming part of this application, and in which:

Fig. 1 is a side view of a sunken submarine provided with my safety appliance.

Fig. 2 is a cross-section through the submarine showing my invention erected.

Fig. 3 is a fragmentary perspective view showing one tube outlet open and an air tube projected therethrough.

Fig. 4 is a section through an outlet, when not in use.

Figs. 5, 6, 7 show three successive stages in the manipulation of the outlets preparatory to the projection of the air tubes.

Fig. 8 is a fragmentary view, partly in section, showing different sections of an air-tube assembled.

Fig. 9 is a push-rod used in connection with this invention.

Fig. 10 is a fragmentary view showing a cross-section of a submarine using my invention when in sunken and listing position.

Fig. 11 is a section through a tube outlet used in connection with listing sunken submarines.

I am aware of the fact that several safety appliances for supplying air to a sunken submarine have been proposed, said appliances consisting generally in the use of a float, releasable from within the submarine, to which a flexible tube, preferably of rubber, is attached, the other end of said tube being secured in the craft and supplying air therein. It appears that this arrangement has not met with successful application, primarily because the flexible tube is liable to get twisted or form into knots or sharp bends which prevent or greatly reduce the entrance or discharge of air. Other reasons for the failure of such arrangement may be found in the collapse of the flexible tube due to hydrostatic pressure and that owing to the practical physical limitations of the float, the air tubes cannot be raised a sufficient height above the level of a stormy sea to prevent the entrance of water therein.

With my invention it is possible for the crew of a sunken submarine to force the rigid air-tubes a sufficient distance above the level of the sea to exclude the entrance of water and also overcome the other dangers such as collapsing or knotting of the air tubes.

Reference being had to the drawings, the submarine S is provided with two identical tube outlets which are mounted on the deck D of the submarine in suitable spaced relation, at I and O. The outlet at I being for the air inlet tube I¹ and the outlet at O being for the air outlet tube O¹.

As shown especially in Figs. 4 to 7 each tube outlet consists of a hub portion 1 secured in any desired manner, such as by welding, to the underside of the deck D. This hub is threaded inwardly, as at 2, to receive the outwardly and inwardly threaded

bushing 3 having a polygonal flange 4 for the application of a wrench or the like.

Screwed into the bushing is the guide-sleeve 5 comprising the head 6 having outward threads 7 throughout its length and interior threads 8 at its upper end; the lower portion 9 which has interior threads 10 at its lower end and the intermediate polygonal flange 11 which is used for screwing the sleeve into the bushing by means of a wrench.

In the sleeve is inserted a muff 12 made of yielding material, preferably felt, which is impregnated with a heavy oil or lubricating grease to make it waterproof and to reduce the frictional engagement with the air tubes to be forced therethrough. The muff has a central aperture 13 which is slightly less than the diameter of the air tube and it is placed in the sleeve member 5 between the upper collar 14 and the lower collar 15. The upper collar is outwardly threaded to engage the threads 8 in the sleeve, and it is preferably made of wood and with rounded corners 16 to prevent any injury to the air-tubes when swayed about by the movement of the boat or by the waves.

The lower collar 15 is made of metal and is threaded outwardly and inwardly. The outer threads fit the threads 10 cut in the sleeve 5 and the inner threads 17 are used to support the air tube, as will be described later. These two collars are screwed into place by means of spanner wrenches which engage special holes 18 provided in the collars.

The felt muff 12 is additionally secured in the sleeve 5 against rotation and collapsing by means of cleats 19 preferably of wood which are embedded in the outer surface of the muff, said cleats being secured to the sleeve by means of screws 20, as shown in the drawing.

The opening provided in the deck for the tube outlet is normally closed by means of a cover 21 which is secured in place by one or more bolts 22 and by the operating spindle 23 provided at the lower end with a slideable handle-bar 24. This spindle is fastened to the cover by a pin 25 and it will be noted that the threaded bolt holes in the cover do not extend therethrough, but are drilled partly in bosses 26; this is done, of course, to prevent any leaks into the submarine. For the same reason, a gasket 27 of rubber, preferably, is inserted between the cover and its seat.

To facilitate the initial turning about the cover, I provide in the cover the equalizer duct 28 which is drilled through a bolt hole and is normally closed by said bolt. When the latter is screwed out, prior to opening the cover, the equalizer duct will be opened thus allowing the sea water to enter on the underside of the cover and counterbalance the hydrostatic pressure thereon.

Each air tube consists of a top section 29, a special bottom section 30 and of as many intermediate sections 31 as are needed to bring the air tube a sufficient distance above the sea-level.

In the top section are provided, adjacent the upper end, one or more openings covered with transparent panes 32 of glass, or other suitable material, having the same curvature as the air tube. The purpose of these windows is to give a visual sign when the air-tube has been raised above the sea level. The various sections are joined together by means of male and female pipe connections 33 formed, preferably, integrally with the pipe sections and arranged to offer a smooth surface in and outside of the pipe. The lower tube section 30 has an enlarged portion in which are cut threads 34 adapted to fit the threads 17 cut in the lower collar 15, for the purpose of supporting the air tube.

When an air tube is first projected upward, section by section, the uppermost tube 29 is closed with a removable cone-headed cap 35 having a reduced portion 36 which frictionally engages the inside of said tube, to prevent water rushing into the submarine during the erection of the air tube.

After an air tube has reached its proper height, the cap 35 is slowly forced off the top section by means of a push-rod 37 built up of sections of small pipe and provided at its upper end with a felt plug 38, having both ends suitably tapered, and fitting snugly within the air tube. An upward push of this rod will remove the cap 35 and establish connection between the sunken submarine and the outside air. Owing to the cheapness of the cap, the latter when removed is wasted, and no provisions need be made to salvage the same. Should the cap be removed too soon, the water entering the air tube would be stopped by the felt plug 38, with the exception of a small amount flowing down the tubular push-rod, and which by its presence would inform the crew that the air tube must be lengthened. A pipe cap 39 at the lower end of the pushrod may be applied to stop the flow of water.

The purpose of inserting the bushing 3 between the hub 1 and the head 6 of the sleeve 5 is to permit of the use of special types of guide-sleeves in case the submarine should acquire a listing position on the sea-bottom.

It will be noted from Fig. 10 that if a straight sleeve of the type shown in Figs. 6 and 7 were used, the air tube would assume an inclined position in the water, and its length would have to be considerably increased to bring it a sufficient distance above the sea level. By using a special sleeve, Fig. 11, in which the head 6'

is suitably enlarged and inclined relative to the vertical lower portion 9', the air tube may be forced up in a vertical direction, which operation is the easiest to perform and requires the shortest length of tubing. In practice, each submarine would be supplied with several sets of special bushings, each designed to compensate for a different inclination of the sunken submarine.

10 Intermediate listings of the craft could be taken care of by simply increasing the length of the air tubes. Aside of the angular disposition and the enlarged size of their heads, these special sleeves are identical with the straight sleeve and the same structural elements are used in combination therewith.

Under normal operating conditions, the outlets (I) and (O) are closed by the covers 21 and by means of threaded plugs 40, 20 screwed into the bushing 3.

Assuming now that the submarine should sink to the bottom of the sea, the crew would proceed substantially as follows: The list, if any, of the boat and the depth under 25 water are first ascertained by means of special instruments found in every modern submarine, to determine the type of guide-sleeve as well as the total length of air tubing required.

30 This done, the plug 40 is removed and a fully assembled guide-sleeve is put in its place. The first section of tubing 29 with its cap 35 is now pushed through the muff by hand or by means of a jack or other lifting device available in the submarine. The cover holding bolt 22 is now screwed out of the cover to free it and allow the equalizer duct 28 to function. The cover may now be swung around by means of the handle-bar 24 of the spindle 23. The first tube section is then pushed up through the outlet and as many intermediate tube sections are joined together, one at a time, and pushed up as required to bring the air tube above 40 the sea level; which condition may be ascertained by looking up the tube and observing the light shining through the windows 32. If the air tube is high enough, the last section 30 is added thereto and screwed into 45 the lower collar 15. The push-rod 37 is then pushed up into the air tube, section by section, to reach and remove the cap 35; thus establishing communication with the outside air.

50 To increase the amount of air delivered into the submarine and the exhaust of foul air therefrom, the air inlet tube (I') is connected by means of additional pipe sections and a T-fitting to a mechanical fan 41, preferably direct connected to an electric motor 42.

Any flooding of the submarine due to 65 accidental rupture or an air tube is prevented by providing each tube with a suitable valve 43 positioned below the guide-

sleeve 5 and which may be shut off in case of emergency.

The air outlet tube (O') opens directly into the submarine and is provided immediately below its valve 43 with additional apertures 44 disposed all around the tube. If desired, this tube may be additionally supported by a stand 45.

The various pipe sections required for the safety appliance are preferably stored on racks 46 conveniently placed in the submarine.

In case of subsequent listing of the submarine, after the air tubes have been opened, any inrushing water would be stopped by closing the valves 43. The lower tube sections, in the air inlet tube for instance, would be disconnected to allow for the introduction of the sealing plug 38 of the push-rod, way up into the top section 29, the valve 43 having again been opened and the lower end of the push-rod plugged up to prevent any flow of water therethrough. Thereupon, the air tube is pulled in, section by section, until the cover 21 may again be closed to permit of the introduction of a special guide-sleeve to suit the new listing position of the boat.

It may also be stated that the upward forcing of the air tube will be assisted by its buoyancy and that the latter will also assist in supporting an air tube in an intermediate inclined position, thus reducing the strains on the lower end of the air tube, where it protrudes from the outlet.

After communication with the air is properly established, the push-rod may be used for projecting visible signals, such as a flag 47, Fig. 9, in day time, or an electric light or flare (not shown) at night time, the sealing plug being, of course, removed.

As will be understood, as suggested herein, there may be slight changes made in the construction and arrangement of the details of my invention without departing from the field and scope of the same, and I intend to include all such variations, as fall within the scope of the appended claims, in this application in which the preferred form only of my invention is disclosed.

I claim:

1. In a submarine ventilating appliance wherein communication with the atmosphere is effected by means of a rigid ventilating tube, an outlet device for said ventilating tube comprising a hub secured inwardly to the deck of the submarine and having therethrough a threaded central aperture; a bushing threaded into said hub and provided throughout with a threaded aperture; a guide-sleeve threaded in said bushing; a muff of yielding material positioned intermediate the ends of the guide-sleeve and having a longitudinal aperture adapted to be engaged frictionally by said

- 15 ventilating tube; clamping collars positioned in the guide-sleeve and effective on both ends of the muff; anchoring means embedded in said muff; means cooperating with said anchoring means to secure the muff to the guide-sleeve, and exterior cover means operable from within the submarine to close said outlet device.
2. In a submarine ventilating appliance 10 wherein communication with the atmosphere is effected by means of a rigid ventilating tube, an outlet device for said ventilating tube comprising a hub secured inwardly to the deck of the submarine and having there- 15 through a threaded central aperture; a bushing threaded into said hub and provided throughout with a threaded aperture; a guide-sleeve threaded in said bushing; a muff of yielding material positioned intermediate the ends of the guide sleeve and having a longitudinal aperture adapted to be engaged frictionally by said ventilating tube; clamping collars positioned in the 20 guide-sleeve and effective on the upper and lower ends of the muff; said collars having through apertures adapted to be engaged by the ventilating tube; the upper collar being made of non-metallic material softer 25 than the ventilating tube and having its aperture rounded at the outer end; the lower collar having its aperture threaded to accommodate the lower threaded end of the 30 ventilating tube; anchoring means embedded in said muff; means cooperating with the 35 anchoring means to removably secure said muff to the guide-sleeve, and an exterior rotatable cover operable from within the submarine to close said outlet device.
3. In a submarine ventilating appliance 40 wherein communication with the atmosphere is effected by means of a rigid ventilating tube, an outlet device for said ventilating tube comprising a hub secured inwardly to the deck of the submarine and having there- 45 through a threaded central aperture; a bushing threaded into said hub and provided throughout with a threaded aperture; a guide sleeve threaded in said bushing; a muff of yielding material positioned intermediate 50 the ends of the guide sleeve and having a longitudinal aperture adapted to be engaged frictionally by said ventilating tube; clamping collars positioned in the guide-sleeve and effective on the upper and lower 55 ends of the muff; said collars having through apertures adapted to be engaged by the ventilating tube; the upper collar being made of non-metallic material softer 60 than the ventilating tube and having its aperture rounded at the outer end; the lower collar having its aperture threaded to accommodate the lower threaded end of the 65 ventilating tube; anchoring means embedded in said muff; means cooperating with the anchoring means to removably secure

said muff to the guide-sleeve; an exterior rotatable cover operable from within the submarine to close said outlet device, and means to equalize the hydrostatic pressure exerted on said cover.

4. In a submarine ventilating appliance 70 wherein communication with the atmosphere is effected by means of a rigid ventilating tube, an outlet device for said ventilating tube comprising a hub secured inwardly to 75 the deck of the submarine and having there- through a threaded central aperture; a bushing threaded into said hub and provided throughout with a threaded aperture; a guide-sleeve threaded in said bushing; a 80 muff of yielding material positioned intermediate the ends of the guide sleeve and having a longitudinal aperture adapted to be engaged frictionally by said ventilating tube; clamping collars positioned in the 85 guide-sleeve and effective on the upper and lower ends of the muff; said collars having through apertures adapted to be engaged by the ventilating tube; the upper collar being made of non-metallic material softer 90 than the ventilating tube and having its aperture rounded at the outer end; the lower collar having its aperture threaded to accommodate the lower threaded end of the 95 ventilating tube; anchoring means embedded in said muff; means cooperating with the anchoring means to removably secure 100 said muff to the guide-sleeve; an exterior rotatable cover operable from within the submarine to close said outlet device; bolt means to lock the cover in closed position; said cover having ducts to introduce hydrostatic pressure on the underside thereof, said ducts being closable by said bolt 105 means.

In testimony whereof I affix my signature.
CHARLES F. EBERT.
